UNITED STATES PATENT OFFICE.

JOHN H. ROBERTSON, OF NEW YORK, N. Y.

CABLE-LIFTER FOR CABLE RAILWAYS.

SPECIFICATION forming part of Letters Patent No. 372,930, dated November 8, 1887.

Application filed April 20, 1887. Serial No. 235,463. (No model.)

To all whom it may concern:

Be it known that I, JOHN H. ROBERTSON, of the city and county of New York, in the State of New York, have invented a new and useful 5 Improvement in Cable-Lifters for Cable Railways, of which the following is a specification.

In the operation of cable railways it is frequently difficult to lift the cable from its supporting-sheaves in the cable-tunnel into range 10 of the grip-jaws. It is common to employ two parallel lines of cable, both moving in the same tunnel and in the same direction, and in case of the cable with which the grip is connected stopping, by reason of the stoppage of the 15 operating-engine, or in case of the cable escaping from the grip, it becomes necessary to lift the escaped cable or the other cable into range of the grip.

My invention relates to cable-lifting devices 20 which consist of arms pivoted in a track-supporting structure, so as to swing in a plane transverse to the line of cable, and by which the cable may be lifted from its ordinary supporting-sheave into range of the grip, said 25 arm to be operated by a connection at the side of the track. In my construction a rock-shaft extends parallel with the line of cable, and is provided with cable-lifting arms which engage with the cable to lift it both in advance 30 of and behind the grip upon a car; and a single connection leads from this rock-shaft to a point adjacent to the track, and through which the rock-shaft may be turned to raise the arm. Where two cables are employed, with one or 35 the other of which cars may be engaged, the arms should be bowed downward from the rock-shaft, or should be of U shape, so that they will serve to lift one cable without coming in contact with the other cable, but will 40 simply raise up under the other cable without lifting it. Each arm may be composed of two sections united by a joint providing for the adjustment in a vertical plane of one section relatively to the other, so that the pulley, with 45 which each arm is provided, may be brought to just the desired vertical position for raising the cable to the level of the grip when operated.

The invention will be hereinafter more fully 50 described, and pointed out in the claims.

In the accompanying drawings, Figure 1 is a transverse section of a cable railway to

which are applied my improved cable-lifters. Fig. 2 is a horizontal section upon about the plane indicated by the dotted line x x, Fig. 1. 55 Fig. 3 is a sectional elevation upon a larger scale, showing a box or casing to which the connection for operating the cable-lifters may be conducted, and through which they may be operated, and such box or casing being arranged at the side of the track, and also showing a key for use in connection therewith; and Figs. 4 and 5 are detail views in planes at right angles to each other, showing a novel construction of joint which may be employed to 60 connect two sections of the cable-lifting arms, as will be hereinafter described.

Similar letters of reference designate corresponding parts in all the figures.

A designates the track-rails, and B designates the slot-bars, between which is maintained a narrow slot, b, for the reception of the plates c, which form the sole connection between the car above the surface and the grip mechanism moving below the surface and in 70 the tunnel D. I have in Fig. 1 shown the grip mechanism in outline. In the tunnel D are also journaled cable supporting sheaves D', upon which two cables may be supported. The track-rails and the slot-bars may be supported in a well-known manner by transverse frames or yokes E, arranged at a suitable distance apart.

In the present example of my invention the cable-lifters are adapted for two cables moving 85 in one tunnel D, and for each cable I have represented a pair of lifters, F, which consist of arms secured upon the rock-shaft F', and provided at their free ends with rollers f. The rock-shaft F' may be suitably journaled in 90 bearings e in the adjacent yokes or transverse frames E, and by turning either rock-shaft the pair of arms F connected therewith will be swung in a plane transverse to the line of movement of the cable. These arms are of 95 such length and are so arranged that when in their lowermost position, as shown by full lines in Fig. 1, their rollers f will have their cable-supporting surfaces coincident with the cable-supporting groove in one sheave D', and, 100 as best shown in Fig. 1, the rollers f have flanges upon one side only, and are destitute of flanges on their other side. When the cable is to be lifted, the arms F upon either

rock-shaft are raised by turning the shaft, so that they come into the position shown by dotted lines in Fig. 1, thereby raising the cable G to the level of the grip-jaws s s', and 5 permitting the cable to slip laterally off the flangeless side of the roller and into the grip. As here represented, the arms F, which project from each rock-shaft, serve to lift the cable which is farthest from that rock-shaft, and 10 are bowed or curved downward in their length, as best shown in Fig. 1, so that in lifting the cable most distant from either rock-shaft they do not come in contact or interfere with the cable nearest that rock-shaft. It is desirable 15 that a definite movement imparted to the lifting-arms F shall bring them into such position that the cable will slip readily from their rollers f into the grip; and to this end I have represented each arm as composed of two sections, the section which carries the roller f being connected with the section upon the rock-shaft by a joint, f', which provides for adjustment of one section on the other. One construction of joint which will provide for 20 such adjustment is represented in Figs. 4 and 5. The adjacent ends of the sections overlap each other, and are pivotally connected by a clamping-screw, f'', and their bearing-surfaces are serrated or provided with interlocking 25 teeth and grooves, as shown at f''' in Fig. 5, and which extend radially from the clamping-screw f''. By loosening this screw the outer section of arm which carries the roller may be turned upon the screw, and by clamping the 30 screw the section may, by its interlocking teeth and grooves, be readily secured in a new relation to the section of the arm which is on the rock-shaft.

Each rock-shaft F' is provided with a third 35 arm, f', from which extends a chain, f'', or other suitable flexible connection, and at the surface of the pavement adjacent to the track is a box or casing, H, into which leads a flexible connection or chain f''' and which is best 40 shown in Fig. 1. This box or casing H is slotted at the side and near the bottom, as at h, and in said slot is mounted a roller, h', along 45 which the chain is carried and from which it passes upward to the plug or plunger H', free 50 to slide within the box or casing H, and held

against downward movement therein by a shoulder, h''. In the top of the plunger or sliding plug is an oblong hole, h³, which may receive an oblong head, h⁴, upon a key, H², such as is shown in Fig. 3 in perspective. 55

When the key is turned to one position, its head h⁴ may be readily inserted through the slot h³, and then by turning the key one-quarter of a turn it may be made to lap across the slot and prevent free withdrawal therefrom, so that by lifting upon the key the plunger or sliding plug H' may be lifted and the cable-lifters F operated through the connection f⁵. 60

What I claim as my invention, and desire to secure by Letters Patent, is— 65

1. The combination, with a cable-supporting sheave, of a cable-lifter consisting of an arm pivoted adjacent to the cable and arranged to swing transversely to the line of cable, and composed of two sections united by a joint 70 providing for the adjustment in a vertical plane of one section relatively to the other, substantially as herein described.

2. The combination, with a cable-supporting sheave, of a rock-shaft extending parallel 75 with the line of cable and provided with cable-lifting arms, and a single connection leading to the rock-shaft and by which it may be turned to operate the arms, substantially as herein described. 80

3. The combination, with two cables and their supporting-sheaves, of cable-lifters consisting of arms pivoted to swing in planes transverse to the line of cables, and each bowed or curved downward, so as to clear one 85 cable in lifting the other, substantially as herein described.

4. The combination, with a cable-railway track and its cable, of a cable-lifter consisting of an arm pivoted adjacent to the cable to swing 90 in a plane transverse to the line of cable, a surface box or casing adjacent to the track, a connection extending from said arm into the box or casing, and a key for insertion into the box or casing for engaging said connection, 95 substantially as herein described.
